UNITED STATES PATENT OFFICE.

MARCO G. ZONGARO, OF PORTLAND, OREGON.

DOUBLE-LINK GUARD.

1,183,710.

Specification of Letters Patent. Patented May 16, 1916.

Application filed June 1, 1915. Serial No. 31,526.

To all whom it may concern:

Be it known that I, MARCO G. ZONGARO, a citizen of the United States, residing at Portland, in the county of Multnomah and 5 State of Oregon, have invented certain new and useful Improvements in Double-Link Guards; and I do declare the following to be a full, clear, and exact description of the invention, such as will enable others skilled 10 in the art to which it appertains to make and use the same.

This invention relates to improvements in open rings or links and more particularly to the closures therefor, and which are 15 known as double link guards.

The object of the invention is to provide a device of this character which is especially designed for use in logging camps for attaching cables employed for use on fallen trees 20 and which is so constructed that the cable may be attached to both members thereof and readily disengaged when desired.

Another object of the invention is to provide a device of this character with simple 25 and efficient means for simultaneously releasing both ends of the cable connected thereto.

Another object is to provide an open link adapted to be quickly connected to adjacent 30 faces and wherein the pulling strain will be brought to bear on opposite members having similar resistance to breakage, and so positioned relatively to a movable closure that an accidental disengagement will be 35 prevented and injury or obstruction to the free operation of the locking closure avoided.

With these and other objects in view, the 40 invention consists of certain novel features of construction, and the combination and arrangement of parts as will be more fully described and claimed.

In the accompanying drawings: Figure 1 represents a side elevation of a link guard 45 constructed in accordance with this invention with the ends of the cable secured to the hooks of the link; Fig. 2 is a longitudinal section; Fig. 3 is a transverse section taken on the line 3—3 of Fig. 2; Fig. 4 is a 50 similar view taken on the line 4—4 of Fig. 2.

In the embodiment illustrated an oblong link 1 is shown having an opening in one side member thereof, thus forming hook shaped ends 2 and 3, the bills 4 of which 55 extend toward each other and are arranged in longitudinal alinement, said bills being

provided in their free terminals with sockets 5 for a purpose to be described. A closure 10 for these hooks 2 and 3 is shown pivotally mounted on the side bar of the 60 link at a point opposite the space between the bills 4 of the hooks 2 and 3 and which is designed to span the space between the bases and the bills of the hooks, the bases 6 of said hooks being joined by a reduced 65 neck 7 having shoulders at its opposite ends which serve as stops for limiting the longitudinal movement of the closure which is pivotally mounted on said neck. This closure 10 is shown in the form of a hollow 70 casing having a tubular bearing member 11 at one end thereof of a size designed to encircle and receive the neck 7 which joins the bases of the hooks 2 and 3 of the link. Projecting from this tubular member 11 is 75 the hollow casing 12, the side walls of which are spaced apart a distance substantially equal to the thickness of the bases of the hooks and tapers toward its free end which is designed to fit between the bills 4 of the 80 hooks 2 and 3, said casing being of a width corresponding to the distance between the bills 4 of said hooks 2 and 3. Disposed within the casing 12 is a substantially U-shaped spring 13, the cross bar of which is 85 provided with a plurality of laterally extending loops 14, five being here shown, two extending in one direction and three in the opposite direction, the central loop being secured to the end wall of the free end of 90 the casing by a rivet or other suitable means. This U-shaped spring is of a size to fit within the casing 12 with the arms 15 thereof arranged in close proximity to and parallel with the side edges of said casing, said arms 95 being provided at their free ends with outwardly projecting laterally extending studs 16 which pass through apertures 17 in the edge walls of the casing 12 adjacent the free outer end thereof and which are so positioned that when the closure is operatively disposed these studs will enter the sockets 5 in the terminals of the bills 4 and thereby 100 reliably hold the closure in position and form two complete members for the link, 105 said closure dividing said link transversely.

Two push buttons or headed pins 18 are mounted to slide laterally in the edge walls of the casing 12 with their inner ends positioned to engage the outer faces of the arms 110 15 of the spring 13 so that when these pins are compressed toward each other these arms

15 are similarly compressed, thereby forcing the studs 16 carried thereby inward and thus releasing them from the sockets 5 of the hook bills.

5 From the above description it will be obvious that should this link be employed for connecting the ends of a cable C which are tied or otherwise engaged with the hooks 2 and 3, that on the closing of the closure 10 10, said ends will be held entirely separated in spaced relation and will exert their pulling action on the curved portion of the hooks which have a similar resistance to breakage, and it will thus not interfere with 15 the operation of the closure in any way. When it is desired to disconnect these cable ends or any other articles with which the link has been attached, it may be readily accomplished by simply pressing together the 20 pins or push buttons 18 at opposite edges of the closure and thus simultaneously disengage the studs 16 from the sockets 5 in the hook bills and thus permit the closure to swing laterally into open position and the 25 hooks 2 and 3 to be readily disengaged from the article or articles with which they were connected.

While this link is shown and described for use in connection with a cable, it is 30 obvious that it may be employed for many other different purposes, the gist of the invention residing in the peculiar means for closing the link and forming a double guard therefor.

35 I claim as my invention:

1. The combination of a link having hook-shaped ends with the bills of said hooks arranged in alinement and spaced apart, a closure for said hooks pivotally 40 mounted on the link at a point opposite the space between the bills thereof, said closure spanning the space between said hook bills and the bases thereof and corresponding in width to the distance between said bills, the 45 terminals of said bills having sockets therein and said closure having spring pressed studs positioned to enter said sockets when the closure is in operative position, and means for simultaneously releasing said 50 studs.

2. The combination of a link having hook-shaped ends with the bills of said hooks arranged in alinement and spaced apart, a closure for said hooks pivotally 55 mounted on the link at a point opposite the space between the bills thereof, said closure spanning the space between said bills, the terminals of said bills having sockets therein, said closure being hollow and having a 60 substantially U-shaped spring mounted therein with its arms positioned at the side edges of the closure, studs carried by the free ends of said arms and extending outwardly in opposite directions through the 65 edges of said closure in position to enter the

sockets of said bills, and means for compressing said arms to release said studs.

3. The combination of a link having hook-shaped ends with the bills of said hooks arranged in alinement and spaced apart, a closure for said hooks pivotally mounted on the link at a point opposite the space between the bills thereof, said closure spanning the space between said hook bills and the bases thereof and corresponding in width to the distance between said bills, the terminals of said bills having sockets therein, said closure being hollow and having a substantially U-shaped spring mounted therein with its arms positioned at the side edges of the closure, studs carried by the free ends of said arms and extending outwardly in opposite directions through the edges of said closure in position to enter the sockets of said bills, and pins slidably 85 in the edge walls of said closure and positioned to engage said arms for compressing them to release said studs.

4. The combination of a link having hook-shaped ends with the bills of said hooks arranged in alinement and spaced apart, a closure for said hooks pivotally mounted on the link at a point opposite the space between the bills thereof, said closure spanning the space between said hook bills and the bases thereof and corresponding in width to the distance between said bills, the terminals of said bills having sockets therein, said closure being hollow and having a substantially U-shaped spring mounted 90 therein with its arms positioned at the side edges of the closure, studs carried by the free ends of said arms and extending outwardly in opposite directions through the edges of said closure in position to enter the sockets of said bills, the cross bar of said spring being provided with a plurality of laterally extending loops to increase the resiliency of said arms, and means for compressing said arms to release said studs. 100

5. A link comprising hook-shaped ends connected at one side of the link by a reduced neck having shoulders at its opposite ends, the other ends of said hooks being spaced apart a distance corresponding to the 115 length of said neck, said free ends of the hooks having longitudinally alined sockets therein, a closure comprising a cylindrical member revolubly mounted on said neck with a hollow casing radiating therefrom and of a length spanning the space between said neck and the free ends of said hooks, said closure being of a width corresponding to the distance between the free ends of the hooks, a substantially U-shaped spring 120 mounted in said casing with the cross bar thereof provided with laterally extending loops, the arms of said spring being positioned at opposite edges of said casing, studs carried by the free ends of said arms 125 130

and extending laterally outward through said casing edges in position to enter the sockets in said free hook ends, and push buttons mounted in the edge walls of said 5 casing and engaging the arms of said spring.

In testimony whereof I have hereunto set

my hand in presence of two subscribing witnesses.

MARCO G. ZONGARO.
